(57) **CLAIM**

The ornamental design for a wall of an escalator, moving walkway, elevator, or lifting apparatus, as shown and described.

DESCRIPTION

The file of this patent contains at least one drawing executed in color. Copies of this patent with color drawings will be provided by the Office upon request and payment of the necessary fee.

The sole FIGURE is a front view of a wall of an escalator, moving walkway, elevator or lifting apparatus.

The broken line surrounding the wall of an escalator, moving walkway, elevator or lifting apparatus depicts the boundaries of the claim and forms no part thereof. The article is flat. Depth forms no part of the claimed design.
